WALTER LINDSEY, OF TORONTO, ONTARIO, CANADA

COMBINED CARD SUPPORT AND DISPLAY STAND

Application filed March 18, 1930. Serial No. 436,837.

My invention relates to improvements in combined card supports and display stands and the object of the invention is to construct a device which in addition to supporting a card will support any goods which it is desired to display; a further object is to construct a device of the knock-down type which will pack flat occupying the minimum of space and yet which may be readily assembled with great facility.

With the above and other objects in view which will hereinafter appear, my invention consists of a combined card support and display stand constructed and arranged all as hereinafter more particularly described and illustrated in the accompanying drawings in which:—

Fig. 1 represents a plan view of a blank adapted to form the display stand.

Fig. 2 is a similar view of a blank adapted to form the card support.

Fig. 3 is a perspective view of the two blanks bent into their required shape and assembled to constitute the complete card support and display stand with the card attached to the former, said view being taken from the display stand side.

Fig. 4 is a similar view to Fig. 3, viewed from the card support side, the card being removed, and

Fig. 5 is a horizontal section through the assembled device.

Like characters of references indicate corresponding parts in the different views.

The card support or easel comprises a front portion 1 to which the card 2 is attached and wing portions 3 adapted to be bent rearwardly at an angle to the portion 1 so as to support the card in a slightly inclined position to the vertical. The central part of the blank forming the card support has a locking member 4 stamped out of it, the lower portion thereof being uncut and connecting the locking member 4 to the lower part of the main portion 1. The top of the locking portion 4 is provided with two spaced apart locking lugs 5 which, when the wing portions 3 are bent rearwardly into their operative position engage the outer side faces thereof and hold them in position,

it being understood that the upper portion 6 of the locking member 4 is bent down into a substantially horizontal position as illustrated in Figs. 3 and 4.

The display stand comprises the back portions 7, the wing portions 8 adapted to be bent forwardly against the card support wing portions 3, and interlocked between them and the lugs 5. A goods supporting portion 9 is formed at the top of the back portion 7 and is bent forwardly into a substantially horizontal position constituting a platform upon which any goods may be displayed. The forward part of the portion 9 terminates in a tongue 10 adapted to be bent downwardly and locked into slots 11 extending downwardly from the upper edges of the wing portions 3. Thus the display stand is detachably interlocked to the card support.

From the above description it will be apparent that the complete card support and display stand consist each of a single piece of material adapted to be bent into the required shape. Prior to or subsequent to use for the purpose for which it is intended the display stand is detached from the card support and both parts can be flattened out into the positions illustrated in Figs. 1 and 2 wherein they may be stacked in the minimum of space. Moreover, owing to the simplicity of construction of the parts, they may be readily and quickly assembled into the complete device and will provide a rigid support both for the card and the goods to be displayed.

What I claim as my invention is:

1. In a combined card support and display stand, the combination with a card support member, of a display stand member comprising a back portion, wing portions adapted to be bent at an angle to the back portion, and a top platform portion, the back, wing and platform portions being formed integrally one with the other, and said display stand member being detachably interlocked with the card support member.

2. In a combined card support and display stand, the combination with a card support member comprising a front por-

tion to which the card is attached, wing portions formed integrally with the front portion and adapted to be bent rearwardly, a locking member formed integrally with the front portion and including lugs adapted to engage the wing portions, a display stand member comprising a back portion, wing portions formed integrally therewith adapted to be bent forwardly against the card support member wing portions and held between them by the lugs in the locking member, a top platform portion formed integrally with the back and wing portions of the display stand, and means on the platform portion for interlocking it with the card support member.

3. In a combined card support and display stand, the combination with a card support member comprising a front portion to which the card is attached, wing portions formed integrally with the front portion and adapted to be bent rearwardly, a locking member formed integrally with the front portion and including lugs adapted to engage the wing portions, a display stand member comprising a back portion, wing portions formed integrally therewith adapted to be bent forwardly against the card support member wing portions and held between them and the lugs in the locking member, a top platform portion formed integrally with the back and wing portions of the display stand, and a depending tongue at the forward edge of the platform portion adapted to lock into slots extending down from the upper edges of the wing portions of the card support member.
